US00D810844S

(12) **United States Design Patent** (10) **Patent No.:** **US D810,844 S**
(45) **Date of Patent:** **** Feb. 20, 2018**

(54) **HAND GRIP EXERCISER**

(71) Applicant: **Dyaco International Inc.**, Taipei (TW)

(72) Inventor: **Kuo-Wo Hao**, Taipei (TW)

(73) Assignee: **Dyaco International Inc.**, Taipei (TW)

(**) Term: **15 Years**

(21) Appl. No.: **29/590,313**

(22) Filed: **Jan. 9, 2017**

(30) **Foreign Application Priority Data**

Dec. 29, 2016 (TW) 105308016

(51) **LOC (11) Cl.** **21-02**

(52) **U.S. Cl.**

USPC **D21/684**

(58) **Field of Classification Search**
